Inventor:
Charles B. Magrath
by Sheridan, Jones and Sheridan Atty's

UNITED STATES PATENT OFFICE.

CHARLES B. MAGRATH, OF CHICAGO, ILLINOIS.

MOBILE POWER MECHANISM.

Application filed April 11, 1923. Serial No. 631,307.

To all whom it may concern:

Be it known that I, CHARLES B. MAGRATH, subject of the King of Great Britain, residing at Chicago, in the county of Cook and 5 State of Illinois, have invented certain new and useful Improvements in Mobile Power Mechanisms, of which the following is a specification.

This invention relates to improvements in 10 mobile power mechanisms, more particularly that class of devices which is supported and movable upon a track.

In the use of this class of devices, as for example, movable steam shovels—as in the 15 embodiment shown in the accompanying drawings—it is customary to lay the track in sections, comprising the usual parallel rail sections and transverse sleepers or ties. As it becomes necessary to move the device 20 forward, it is customary in present day practice to either utilize the efforts of a large number of workmen to move the rear section of the track to the front thereof, or more frequently to disassemble a rear section, 25 carry the elements thereof to the front and re-assemble them in alinement with the track.

The object of my invention is to expedite 30 this handling of the track sections and to eliminate the services of a relatively large number of laborers now required.

I accomplish this object by providing a 35 track or rail attached to and supported by the device itself and extending from a point at the rear of the body to a point at the side and adjacent the front thereof. At the front terminus of this rail I provide a 40 swinging post crane having a rail section alinable with the main rail. Hoisting means is provided attached to a trolley, 45 which runs upon the rail by means of which a complete track section may be lifted and moved with the trolley upon the rail section carried by the crane and thereafter 50 swung to a position in front of the device into alinement with the remainder of the track.

Other objects of my invention relate to 55 the elements and details of construction enabling me to accomplish this object.

In the following specification and accompanying drawings I have described and shown one embodiment of my invention. In the drawings—

56 Figure 1 is a side elevation partially

diagrammatic, illustrating my invention as applied to a mobile steam shovel;

Fig. 2 is a plan view of the rail and crane structure, the body of the device being indicated in outline;

Fig. 3 is a plan view of the supporting track, the rail of the device being indicated in dotted lines together with the limit positions of the post crane;

Fig. 4 is a vertical section along the line 65 4, 4 of Fig. 2, the trolley being indicated in dotted lines;

Fig. 5 is a detail elevation of the trolley and hoisting means, showing the engagement with a section of the track;

Fig. 6 is a side elevation of a portion of 70 the main trolley carrying rail and the crane rail showing the latter in alinement therewith, the blocking position of the latch being indicated in dotted lines;

Fig. 7 is a section along the line 7, 7 75 of Fig. 6; and

Fig. 8 is a vertical section along the line 8, 8 of Fig. 6.

Like numerals refer to like elements 80 throughout the drawings in which 10 designates generally a steam shovel having the supporting trucks 11 carried by the wheels 12. At the front of the device is provided the usual circle 13 carrying the scoop beams 85 and other elements not forming a part of the present invention.

The body 10^a of the shovel is carried upon the longitudinal beams or sills 14—15, of I-construction as shown in Figure 4, for example. Carried by the device is the rail 16 parallel to and spaced from one side of the body 10^a along the major portion of its length and curving around parallel to the rear end of said body, as shown in Fig. 2, 90 for example. This angular rear portion 16^a is supported by the hangers 18 and 19, projecting outwardly from the body of the shovel, as shown in Figs. 1 and 2, for example. The rail 16 is of I-beam construction, the lower flange 16^b serving as the supporting track for a trolley 20, of conventional construction, as shown in Figs. 4 and 5, for example. Supporting strips or plates 22 project outwardly from sill 14 and 95 are secured thereto by clamps 14^a and bolts 14^b, being secured at the outer extremity to the upper flange of rail 16 by means of the bolts or rivets 23. Braces 24 are similarly secured to the lower flange of sill 14 100 and 105

and are inclined upwardly toward and attached to the plates 22 by bolts 25, see Fig. 4. The front end 16^b of the rail 16 terminates at a point short of the front of the shovel 5 and alinable therewith is a rail section 30, depending from and secured to an I-beam 32, which overlies it, this I-beam being attached to the upright post 33 and securely tied thereto by the tie bar 34, these elements 10 comprising a post crane of well known construction, a suitable bearing plate 36 being provided at the top of the post 33, and a support 37 being provided at the lower end, post 33 being journaled between these members, as shown in Fig. 1, and in the embodiment shown, preferably inclined outwardly from top to bottom. The range of movement of the horizontal I-beam 32 is indicated in dotted lines in Fig. 3, the beam 20 32 being located beneath the circle 13 and arranged and constructed to pass partially thereunder for a purpose to be hereinafter described.

The rail end 16^b is provided with the upwardly projecting fin 40, and secured to the upper flange of the rail 16 by rivets 40^a, or the like. This fin is provided with an aperture therein indicated by numeral 40^b. A plate 45 is suitably secured to the outer 25 end of the beam 32, the lower corner of the beam 32 being cut away along the dotted line 32^c, as indicated in Fig. 6. The plate 45 is bent, or offset, below the beam 32 to substantially aline with the web thereof. 30 Adjacent its lower corner, the plate 45 is provided with the hole or aperture 45^a, through which extends a headed pin 47. Pivoted upon the pin 47 at either side of the plate 45 is the U-shaped latch 50 having 35 the free ends thereof curved as indicated at 50^a. Adjacent the closed end the latch 50 is provided with the elongated slot 50^b. This latch 50 is movable to a position engaging the fin 40 with the slot 50^b in alinement with hole 40^b, a locking pin or key being insertable through both to lock the rail section 30 in alinement with the rail 16 as shown in Figure 6.

The latch 50 is so constructed and arranged that a portion thereof to the right of the hinge pin 47, as viewed in Fig. 6, is heavier than the opposite portion and when the pin 51 is removed, the latch 50 will tilt to position indicated in dotted lines in Fig. 6, this being termed "block position."

At the opposite end the rail section 30 is provided with filler blocks 30^a for a purpose hereinafter described.

Swiveled to the trolley 20 and depending therefrom is the pulley hoist, generally indicated by numeral 55, this being of well known construction, and provided with four grab hooks 56 at its lower end, likewise swiveled through the medium of block 57.

The wheels 12, mounted upon the track-

way 60, constructed in sections 60^a, each comprising a pair of parallel rail sections 60^b, carried by and attached to the cross ties or sleepers 60^c.

In the operation of the structure described, the trolley is moved to the position shown in Fig. 1 overlying the section of track to be moved and the grab hooks 56 placed in engagement with the rail section 60^b, after which the hoist 55 is operated in well known manner to lift the rail section to the height desired. The trolley and hoist are then moved along the rail 16 and onto the rail section 30, after which the pin 51 is removed, whereupon the latch 50 will move to block position, preventing accidental movement of the trolley from the section 30. The blocks 30^a limit movement in the opposite direction of the trolley 20, as will be obvious. The post crane may then be rotated so that the beam 32 will swing to the position, for example, indicated by dotted lines in Fig. 3, with the track section in alinement with the remainder of the trackway, when the hoist may be operated to lower the track section and to prevent the release of the grab hooks. After this the post crane is swung to alined position and locked therein by the latch 50. The trolley is then moved to position at the rear of the body 10^a ready for further use.

The arrangement and positioning of the beam 32 with respect to the platform or circle 13, permits the swinging of the former under the latter to proper alined position of the track sections of the trackway, so that the lifting or placing of the moved track section other than that accomplished by the hoist is unnecessary, so that in ordinary operation one laborer may accomplish what would require a large number of men a considerable time in present day practice.

It will be apparent that my invention is susceptible of modification and I do not wish to be restricted to the embodiment shown and described, except as defined in the appended claims.

What I claim is—

1. In combination, a device of the character described, a rail carried by said device, carrying means movable on said rail, a crane carried by said device, a rail section alinable with said rail and carried by said crane, said crane being movable to move said section from said alinement to a desired position, said carrying means being movable from said rail onto said rail section, and means to prevent accidental movement of said carrying means from said section.

2. In combination, a device of the character described, a rail carried by said device, carrying means movable on said rail, a crane carried by said device, a rail section alinable with said rail and carried by said crane, said crane being movable to move said

section from said alinement to a desired position, means to lock said section in alinement with said rail, said means comprising a latch member movable with said section, said carrying means being movable onto said rail section, said latch member being mounted to normally move to a block position to prevent accidental movement of said carrying means off said rail section.

10 3. In structure of the class described, a rail, a swinging beam, a rail section carried thereby and alinable with said rail, means to lock said rail and rail section in alined position, said means comprising a fin carried by one of said members and a pivoted latch engageable with said fin and carried by the other of said members.

4. In structure of the class described, a rail, a swinging beam, a rail section carried thereby and alinable with said rail, means to lock said rail and rail section in alined position, said means comprising a fin carried by one of said members and a pivoted latch engageable with said fin and carried by the other of said members, said fin and latch being apertured to permit insertion of a locking pin therethrough.

5. In mechanism of the class described, a rail, a swinging beam, a rail section carried thereby and movable into alinement with said rail, a pivoted latch carried by said section, means engageable by said latch to lock said rail section to said rail, said latch being so mounted as to normally cause one end thereof to move to block position with respect to said section.

6. In combination, with a device of the character described, comprising a supporting frame and a body carried thereby, a rail spaced from said frame, a supporting means movably mounted on said rail, a hoisting means carried by said supporting means, a track rail engaging means carried by said hoisting means, a swinging crane carried by said frame and provided with a rail section alinable with said rail, said supporting means being movable onto said rail section when the latter is in alinement with said rail, and means to normally prevent return movement of said carrying means.

7. In combination with a device of the character described, comprising a supporting frame and a body carried thereby, a rail spaced from said frame, a supporting means movably mounted on said rail, a hoisting means carried by said supporting means, a track rail engaging means carried by said hoisting means, a swinging crane carried by said frame and provided with a rail section alinable with said rail, said supporting means being movable onto said rail section when the latter is in alinement with said rail, and means to normally prevent return movement of said carrying means, said last named means being engageable with said

rail to lock said section in alinement therewith.

8. In combination with a device of the character described, comprising a supporting frame, a body carried thereby, and a rotatable circle at one end thereof, a rail spaced from said frame parallel to one side thereof and having an angularly disposed portion parallel to the rear end thereof, a trolley member movable on said rail, a swinging crane supported upon said frame, and a rail section alinable with said rail and carried by said crane, said section being movable with said crane to a position underlying said circle at the front of said device. 75

9. In combination with a device of the character described, comprising a supporting frame, a body carried thereby, a rotatable circle at one end thereof, a rail spaced from said frame parallel to one side thereof and having an angularly disposed portion parallel to the rear end thereof, a trolley member movable on said rail, a swinging crane supported upon said frame, a rail section alinable with said rail and carried by said crane, 90 said section being movable with said crane to a position underlying said circle at the front of said device, and a trackway engaging and hoisting means carried by said trolley member. 95

10. In combination with a device of the character described, comprising a supporting frame, a body carried thereby, a rotatable circle at one end thereof, a rail spaced from said frame parallel to one side thereof and having an angularly disposed portion parallel to the rear end thereof, a trolley member movable on said rail, a swinging crane supported upon said frame, a rail section alinable with said rail and carried by said crane, said section being movable with said crane to a position underlying said circle at the front of said device, and a trackway engaging and hoisting means carried by said trolley member, said trolley member 100 110 being movable onto said rail section.

11. In combination with a device of the character described, comprising a supporting frame, a body carried thereby, a rotatable circle at one end thereof, a rail spaced from said frame parallel to one side thereof and having an angularly disposed portion parallel to the rear end thereof, a trolley member movable on said rail, a swinging crane supported upon said frame, a rail section alinable with said rail and carried by said crane, said section being movable with said crane to a position underlying said circle at the front of said device, a trackway engaging and hoisting means carried by said trolley member, said trolley member being movable onto said rail section, and means engageable with said rail and carried by said rail section, said last named means being normally projectable to prevent move- 115 120 125 130

ment of said trolley member off from said rail section.

12. In structure of the class described, a rail, a swinging beam, a rail section carried thereby and alinable with said rail, means to lock said rail and rail section in alined position, said means comprising a fin carried by one of said members and a piv-

oted latch engageable with said fin and carried by the other of said members, said latch having a looped portion fitting over said fin.

In testimony whereof, I have subscribed my name.

CHARLES B. MAGRATH.
